UNITED STATES PATENT OFFICE.

WILLIAM A. J. KOHRN, OF SAN FRANCISCO, CALIFORNIA.

TELEGRAPH-KEY.

SPECIFICATION forming part of Letters Patent No. 439,959, dated November 4, 1890.

Application filed May 10, 1890. Serial No. 351,236. (No model.)

To all whom it may concern:

Be it known that I, WILLIAM A. J. KOHRN, of San Francisco, in the county of San Francisco and State of California, have invented 5 a new and useful Improvement in Telegraph-Keys, of which the following is a specification, reference being had to the annexed drawings, forming a part thereof, in which—

Figure 1 is a plan view of my improved 10 telegraph-key. Fig. 2 is a plan view of the circuit-closing switch. Fig. 3 is a side elevation, and Fig. 4 is a transverse section taken on line $x-x$ in Fig. 2.

Similar letters of reference indicate corresponding parts in all the views.

The object of my invention is to provide a telegraph-key in which the circuit will be perfectly closed by the circuit-closing switch, and in which at the same time the contact- 20 points will be brought together, so as to prevent any accumulation of dirt upon the contact-surfaces.

My invention consists in the combination, with the key, of a circuit-closing switch pivoted to the frame of the key and adapted to swing under the anvil-tongue in the usual way, and provided with a beveled arm arranged to engage a spring projecting downwardly from the key-lever, so as to force the 30 rear end of the key-lever upward, closing the circuit at the contact-points of the key as well as between the circuit-closing switch and the anvil-tongue, all as will be hereinafter more fully described.

The trunnions a of the key-lever A are pivoted in screws b , passing through ears c on the frame B. To the front of the frame is attached the usual anvil C, provided with the contact-point d and tongue e . The key-lever 40 A is furnished with a contact-point f , arranged opposite the contact-point d of the anvil C. To the under surface of the key-lever A, be-

tween the trunnions a and the rear end of the lever, is secured a flat spring D, extending downwardly and rearwardly with its free end 45 turned up toward the key-lever, as shown.

To the frame B, in the right-hand side thereof, is pivoted a circuit-closing lever E, provided with the curved finger g , which extends rearwardly and is provided with the 50 beveled or wedge-shaped end h , as shown in Figs. 3 and 4. The circuit-closing lever E is capable of sliding under the tongue e , and its wedge-shaped end is adapted to slide under the free end of the spring D, causing the key- 55 lever A to tilt and bring the point f into contact with the point d . It will thus be seen that the circuit is closed through the contact-points of the key, and also through the circuit-closing lever E. By means of this double 60 device the closing of the circuit is insured whenever the lever E is moved toward the anvil C.

Having thus described my invention, I claim as new and desire to secure by Letters 65 Patent—

1. The combination, with a telegraph-key, of a circuit-closing lever pivoted to the key-base and provided with a curved finger adapted to force the contact-point of the key- 70 lever into contact with the anvil-point, substantially as specified.

2. In a telegraph-key, the combination of the key-lever A, provided with the contact-point f , the spring D, attached to the key-lever, and the circuit-closing lever E, adapted to slide under the anvil-tongue e , and provided with the curved finger g for engaging the spring D, substantially as specified.

WILLIAM A. J. KOHRN.
